CLAIM

The ornamental design for an accent strip for an indirect lighting fixture, as shown and described.

DESCRIPTION

FIG. 1 is a fragmentary top perspective view of an accent strip for an indirect lighting fixture on a reduced scale showing our new design;

FIG. 2 is a fragmentary front elevational view thereof;

FIG. 3 is a fragmentary rear elevational view thereof;

FIG. 4 is a fragmentary top plan view thereof;

FIG. 5 is a fragmentary bottom plan view thereof;

FIG. 6 is a cross-sectional view thereof taken along line 6—6 of FIG. 1.

The broken line representations of an indirect lighting fixture in FIGS. 1 and 6 are for illustrative purposes only and indicate the nature and use of our new design. The strip is broken away to indicate indefinite length.
